W. G. Woolard
ATTORNEY

UNITED STATES PATENT OFFICE

CHARLES F. DEGNER, OF CHICAGO, ILLINOIS

CONDIMENT SHAKER

Application filed April 22, 1932. Serial No. 606,817.

The invention relates to condiment shakers, generally employed as salt and pepper shakers in dining table use, but capable of use in other relations.

5 It resides in a tubular container, closed permanently at its upper end, and closed at its bottom by a removable plug which may be withdrawn for the purpose of filling or replenishing the container. The upper end 10 or top of the container is provided with a plurality of perforations, which, in separate shakers, may vary in diameter to accord with the desired use of the device.

The body of the tubular container is composed of sections which decrease progressively in diameter, from the bottom to the top, so as to present interiorly a like succession of hollow sections of progressively decreasing diameter, and so form at the juncture of 15 the adjoining sections, an annular shoulder, the purpose of which is to break up the salt, should the latter become congested through the absorption of moisture, evaporation of moisture, or other cause tending to 20 produce such condition.

I have found that the use of a certain material in the manufacture of the container is conducive to a free flowing of the contents, due to conditions present which I am not 25 now able to explain.

Having thus outlined the invention, I will now describe the construction illustrated, and in the appended claims will point out the novelty residing therein.

30 In the accompanying drawing:

Figure 1 is a plan view of a device constructed in accordance with my invention.

Fig. 2 is a view in side elevation thereof.

Fig. 3 is a bottom plan view of the same.

Fig. 4 is a vertical central sectional view 40 of the device; and

Fig. 5 is a view in elevation of the screw plug employed to close the opening in the bottom of the container.

45 In the drawing, the condiment shaker is illustrated as a tubular container A, the open bottom of which is closed by a screw plug B, and the closed or top end C of which is provided with a plurality of perforations as at

10, through which the contents may be sifted in the usual manner.

The tubular container A is formed of a plurality of sections 11, 12, 13 and 14, joined integrally to constitute a one-piece structure, 55 and progressively decreasing in diameter from the base 15, to the upper end of the same. The thickness of the walls of the several sections is approximately the same, so that there is produced interiorly of the casting, a like succession of hollow sections of reduced diameter, proportioned to the external diameters of such sections. In this manner, the interior is provided at the junction of the meeting line of adjoining sections 60 with annular shoulders 16, 17 and 18, each of which overhangs the next lower section of larger diameter.

The opening in the base 15 is threaded for the reception of the inset plug B, the latter 70 being threaded on its periphery as at 19, to engage the interiorly threaded base. The plug B is hollowed out at its underside, as shown in Fig. 4, and is provided with a transversely extending rib 20, constituting a 75 means whereby the plug may be screwed into position, to close the lower end of the container, and unscrewed therefrom, to permit filling or replenishment of the container with the condiment to be sifted through the perforations 10 at the top of the same. The plug B is formed preferably with a flat top surface, and with a cylindrical end 21, which latter is adapted to enter the hollow of the section 11.

80 The line joining the lower end of the section 11 to the base 15, is the weakest part of the structure, and I guard against possible fracture therein by providing some vertically standing spaced projections 22, which 85 more firmly unite the base to the said section.

The openings 10 at the top of the shaker may be varied in size, in the different shakers, to adapt the devices to be used as dispensers of condiments of different characteristics.

90 Table salt has a great affinity for moist air, and when so charged, is converted into a mass having an objectionable cohesion of its granular substance, which will prevent the flow 95 100

of the salt through the perforations, when it is desired to make use of the device. Under such conditions, agitation of a shaker in the direction of its longitudinal axis will cause the packed salt to be thrown against the several interior shoulders, with the result that the mass will be broken up and the cohesion destroyed, so that the granular substance will then run freely through the openings 10.

- 10 I have found the material known in commerce as "bakelite", particularly well adapted for use in the manufacture of the container and its closing plug, inasmuch as such material may readily be moulded into the desired shape. Bakelite is not liable to easy fracture, and manifests a peculiar property, in that it retards the effect of moisture upon the condiment, particularly in the case of salt, whereby in the use of such material the tendency of the condiment to pack down or become solidified, is greatly reduced.
- 15 Having thus described my invention, what I claim and desire to secure by Letters Patent of the United States, is:
- 20 1. A condiment shaker formed as a tubular container perforated at its closed upper end to permit movement of the contents therethrough, and a removable plug closing the bottom end of the same to permit filling and replenishment of the container, the said container being constituted integrally of a plurality of sections of progressively reduced diameter, whereby there is produced upon the inside of the container a succession of annular shoulders at the ends of the adjoining sections, serving to break up a mass formed within the container.

- 25 2. A condiment shaker formed as a tubular container perforated at its closed upper end to permit movement of the contents therethrough, and a removable plug threaded into the bottom end of the same to permit filling and replenishment of the container, the said container being constituted integrally of a plurality of sections of progressively reduced diameter, whereby there is produced upon the inside of the container a succession of annular shoulders at the ends of the adjoining sections, serving to break up a mass formed within the container.
- 30 3. A condiment shaker formed as a tubular container having an upper section of reduced diameter and perforated at its end to allow movement of the contents therethrough, and a lower section of larger diameter, with an intermediate section of reduced diameter, whereby there is produced a succession of annular shoulders at the ends of the adjoining sections, serving to break up a mass formed within the container, and a removable plug closing the bottom of the same to permit filling and replenishment of the container.
- 35 4. A condiment shaker formed as a tubular container having an upper section of reduced diameter and perforated at its end to allow

movement of the contents therethrough, and a lower section of larger diameter, with a plurality of intermediate sections of progressively reduced diameter, whereby there is produced upon the inside of the container, a succession of annular shoulders at the ends of the adjoining sections, serving to break up a mass formed within the container, and a removable plug closing the bottom of the same to permit filling and replenishment of the container.

In testimony whereof, I have signed my name at Chicago, this 11th day of April, 1932.

CHARLES F. DEGNER.
